CLAIM

The ornamental design for a computer monitor for access to telephone and computer related services in commercial aircraft, as shown and described.

DESCRIPTION

FIG. 1 is a reduced top front and left side perspective view of a computer monitor for access to telephone and computer related services in commercial aircraft showing our new design;

FIG. 2 is a right side elevational view thereof;

FIG. 3 is a top plan view thereof;

FIG. 4 is a front elevational view thereof;

FIG. 5 is a rear elevational view thereof; and,

FIG. 6 is a bottom plan view thereof.
